TO THE ENGELN ELECTRIC COMPANY, OF CLEVELAND, OHIO, A CORPORATION OF
OHIO.

APPLICATOR-SECURING MEANS.

Application filed February 14, 1927. Serial No. 168,050

This invention relates to securing means for applicators whereby the same may be readily and yieldably secured in various positions and on various parts of the human body for treating the same, and as readily removed therefrom.

An applicator of the type to which this invention is especially adapted comprises an electrode plate presenting a contact surface of conformation to fit that portion of the body which is to be treated, and carrying on its back surface means for connecting the electrode in the treating circuit. Ordinarily to prevent burning it is necessary that good contact with the body be maintained preferably throughout the surface of the plate; to allow for circulation, however, the plate must be yieldably secured in position.

According to our invention we secure the plate with a member of readily flexible elastic webbing by novel means which allow engagement between the plate and webbing in any desirable relation or adjustment, and without mutilating the webbing; or when a more permanent engagement is desired, by perforation of the webbing, provide a positive interlock therewith.

The exact nature of the invention will be apparent from the following description taken in connection with the accompanying drawings in which Fig. 1 is a back view of an electrode chosen as an example in which our securing means are incorporated and showing a piece of webbing secured with the electrode thereby; Fig. 2 is a side view of the same partly in section to show details of the means by which the webbing is secured; and Fig. 3 is a detail sectional view showing an alternate and more permanent manner of securing the webbing by our securing means.

Referring now to the drawings, 1 is the electrode proper comprising a plate of generally arcuate conformation on the back of which is an integral lug 2 carrying terminals by which the electrode may be connected in the treating circuit. The electrode is shaped to fit the portion of the human body for which it was designed, the particular electrode illustrated for example would fit around a limb such as the leg at its calf.

In employing the electrode, as stated above a firm contact with the body must be established throughout its inner surface and the electrode must be insulated from other objects than are in the circuit. Moreover,

many electrical treatments require some considerable duration of the application. For all these reasons provision must be made for securing the electrode in operative position, firmly, yet in a manner so as not to impede the blood circulation of the patient.

The conditions recited dictate the employment for the purpose, of a band of readily flexible textile material, preferably of an elastic nature, such as the well known elastic webbing in which parallel threads of rubber are interwoven in such manner that the webbing is extensible in a longitudinal direction. A band of such material forms an ideal medium for securing such an applicator.

According to our invention we provide on the body portion of the electrode, as one adjacent each end thereof, an upstanding projection 3 of the peculiar form illustrated having an undercut base portion and preferably terminating in a bluntly pointed nib portion, the two described portions forming between them an overhanging shoulder or blunt edge. The projection is preferably of circular section, so that the shoulder is circular and the nib portion coniform.

We have found that with such a projection it is possible to secure a webbing such as described, the shoulder of the projection engaging the threads of the webbing to hold the same under tension, but without perforating it. This engagement is easily accomplished by pressing the webbing, as by the thumb, around and particularly back of and against the projection, as tension is applied, and is in the nature of frictional engagement.

When a more permanent engagement is desired, as for example at one end of the webbing, to form a "secured" end, the projection may be punched through the webbing, the point of the nib portion being sufficiently sharp to pierce the webbing when pressed directly against it, this arrangement being shown in Fig. 3. When thus secured upon the projection, the webbing is secured from unintentional removal therefrom by the overhanging circular edge thereof already described.

When properly applied the webbing "free" end assumes a position as indicated in Figs. 1 and 2, in actual use the opposite or secured end having been secured in the same manner or as indicated in Fig. 3 on the opposite projection. Where the electrode is of larger area, obviously, a number of projec-

tions may be employed in connection with a wider securing belt if necessary.

In employing the arrangement described the position of the projections in the webbing will be rarely, if ever, duplicated, but since the webbing is not injured in any way by the projection employed as indicated in Figs. 1 and 2, in any event the webbing will last up to the life of the elastic members. It will be noted that the points of the projections are so small and blunt as to be incapable of effecting any accidental bodily injury, or injury to the webbing, although capable of perforating the webbing if desired.

It will be evident also, that the invention is equally applicable for similar employment in connection with applicators other than the electrode chosen for illustration.

What we claim is:

- 20 1. In an applicator having a body portion, a projection upstanding therefrom and having an undercut base portion and a nib portion, the projection portions forming therebetween an edge overhanging the base portion and adapted for engagement with a securing band of elastic webbing applied flatwise to said body portion.
- 25 2. In an applicator having a body portion, a projection upstanding therefrom and having

an under cut base portion and a coniform nib portion, the projection portions forming therebetween a circular blunt edge overhanging the base portion and adapted for frictional engagement with a securing band of elastic webbing applied flatwise to said body portion, said nib portion being adapted to pierce said band and said edge being adapted to retain the same when pierced, as an optional manner of securing the band.

3. In an applicator having a body portion, a pair of projections upstanding therefrom and each having an undercut base portion and a nib portion, said portions of each projection forming therebetween an overhanging edge whereby one end of a securing band of elastic webbing may be pierced by the nib portion of either of said projections, and be retained on said projection by the overhanging edge thereof, and the other end of said band may be applied flatwise to said applicator body portion and frictionally engaged with said edge thereof to yieldably secure the applicator upon a limb.

In testimony whereof we hereby affix our signatures.

EDWIN R. GOLDFIELD.
CAPERTON HORSLEY.
